John F. O'Malley

UNITED STATES PATENT OFFICE.

JAMES R. WALKER, OF SPRINGWELLS, MICHIGAN.

HARROW.

SPECIFICATION forming part of Letters Patent No. 237,789, dated February 15, 1881.

Application filed January 15, 1879.

To all whom it may concern:

Be it known that I, JAMES R. WALKER, of Springwells, Wayne county, Michigan, have invented an Improvement in Harrows, of which 5 the following is a specification.

The nature of my invention relates to new and useful improvements in the construction of sectional folding harrows, so constructed that the various sections may be interchanged 10 with each other or reversed end for end; and the invention consists in the peculiar construction of the parts, as more fully hereinafter set forth.

In the drawings, Figure 1 is a plan view, 15 showing a harrow in two sections, to which others of similar construction may be added at will. Fig. 2 is an end elevation of the same. Fig. 3 is an enlarged elevation of one of the teeth. Fig. 4 is a cross-section of the same, 20 showing the diamond shape of the tooth and its oval neck. Fig. 5 is a longitudinal section through one of the bars at a point where a tooth is inserted.

In the accompanying drawings, which form 25 a part of this specification, there are shown two sections of a sectional folding harrow, each section of which is composed of two horizontal bars, A, bent into such form, substantially as shown, that when moved directly forward each 30 tooth (there being five provided to each bar) will follow its own line, and the various lines made by the separate teeth will be at equal distances apart. These teeth B are made pointed and diamond-shaped in cross-section, 35 as shown in Fig. 4, and each provided at its upper end with a neck, a, of oval form, without a shoulder, and gradually tapering upward, as seen in Fig. 5, and terminating in a threaded bolt, b, at its upper end. By constructing the 40 neck of the tooth without a shoulder the neck can be rolled into shape from steel or iron bars, while with shoulders they have to be hammered between dies, which is more expensive. The shoulders, also, are liable to be broken off 45 in use, or rounded off, rendering it impossible to hold the tooth steady any length of time. These heads a are inserted into correspondingly-shaped sockets i in the bars A, so that the bolt end of the tooth projects above the 50 bar to receive the cross ties or girts C, by

means of which the bars A are held together in pairs, and the teeth are secured in that position by means of the nuts b, thereby rigidly securing the bars, girts, and teeth together in such manner that the teeth cannot turn in their 5 sockets. The end girts, D, are longer than the intermediate girts, C, and project beyond the sides of the bars, as shown, and one end of each of said end girts is enlarged, as shown at c, which enlargement is provided with a vertical slot. The opposite end terminates in a hook, d, partially turned back upon itself, and these ends are so arranged with relation to each other that the various sections composing the harrow may be interlocked by inserting the hooks through the slots of the adjoining sections, so that one section may be interchanged with another or reversed in its position, as may be desired or convenience may require. Each section is provided at each end with a draw-hook, E, to which the draw-bar F is attached. This draw-hook is pivotally secured to the second girt from each end, by slipping its end over the projecting end of the tooth-bolt, and projects forward over the end girt. Should this draw-hook be rigidly attached and the harrow not be equally balanced, the forward motion of the harrow would be apt to be at an angle to the direct line of draft. To remedy this defect each of the end girts is provided with a slot, c, through which a suitable bolt or set-screw, f, will pass into the draw-hook, and by these means said hook may be adjusted as required.

I am aware that sectional folding harrows have been heretofore constructed and are in common use, consequently I do not broadly claim the invention thereof; but

What I claim, and desire to secure by Letters Patent, is—

1. In a sectional harrow, the combination, with the longitudinal bars A, bent as described, and connected together by the intermediate transverse girts, C, and end girts, both secured to the longitudinal bars by the harrow-teeth, of the end girts, D, each provided with a slot, c, draw-hooks E', each pivoted at its inner end to one of the transverse girts by an upwardly-tapering harrow-tooth, adjusting-bolts f, rings o, and draw-bar F, the whole constructed, ar-

ranged, and operated substantially as described.

2. The combination, with the harrow-tooth, B, having an oval neck, without a shoulder, and gradually tapering from its base upward and terminating in a threaded bolt, h, of a longitudinal harrow-bar, A, having a correspond-

ingly-formed socket made longitudinally therein, cross-girt C, and nut b, substantially as described, and for the purpose set forth.

JAMES R. WALKER.
